UNITED STATES PATENT OFFICE.

DOUGLAS K. WARNER, OF NEW HAVEN, CONNECTICUT.

SNOW-REMOVAL APPARATUS.

1,327,645.

Specification of Letters Patent. Patented Jan. 13, 1920.

Application filed April 9, 1915. Serial No. 20,215.

To all whom it may concern:

Be it known that I, DOUGLAS K. WARNER, a citizen of the United States, residing at New Haven, in the county of New Haven and State of Connecticut, have invented certain new and useful Improvements in Snow-Removal Apparatus, of which the following is a full, clear, and concise description.

The present invention relates generally to improvements in snow removal apparatus and is more specifically directed to an apparatus for this purpose, which will be especially adaptable to the requirements of street railways and other public carriers.

Many attempts have been made to devise an efficient snow removal apparatus, which would be especially applicable to the requirements of traction companies operating in the streets of large cities, where the traffic conditions make it necessary to clean the streets and railway lines with despatch and in an economical manner. However, so far as is known, none of these efforts have proven successful by reason of the fact that the proper means were not provided to admit of the removal of the snow without seriously impeding or interrupting traffic and without subjecting the traction companies or those taking care of the snow removal to a considerable expense.

The principal object of the present invention is to provide a snow removal apparatus, which may be readily employed by power operated traction companies, which will be economical in operation, which will be efficient in service, and which will be so constructed that when the apparatus is not in use the various parts thereof may be readily disassembled for storage purposes.

A further object of the present invention is to provide a snow removal apparatus, embodying the characteristics heretofore recited, wherein the operating parts are arranged for adjustment to suit different conditions of use and also to enable certain projecting parts to be moved to different positions to permit the passing of other vehicles so that traffic is not obstructed when the apparatus is in use.

My invention further contemplates in conjunction with the features enumerated and the advantages set forth, a means whereby in the operation of my snow removal apparatus, the snow removed from the road bed will be automatically transferred or dumped upon a carrier, the carrier being adjustably

coupled to the snow removal apparatus, so that the snow discharged from the removal apparatus into the carrier will be distributed upon the latter to insure a full load. 60

My invention is also directed to a snow removal apparatus, which may be propelled and operated by its own power, or through power from other sources, which is adapted to operate on street car or other rails or 65 which may be provided with the ordinary vehicle traction wheels to render it capable of employment under any and all conditions where an apparatus of this character may be used. 70

In order to afford a clear and comprehensive understanding of my invention, I have shown certain specific embodiments thereof in the accompanying drawings, but I would have it understood that I do not 75 limit myself to the details of structure of these embodiments nor to the particular arrangement of parts therein shown, reserving unto myself the full range of equivalents to which I would be entitled under the spirit 80 and scope of my invention in its broadest aspect.

I shall now proceed to describe my invention with reference to the accompanying drawings and then point out more specifically, the essential elements of novelty therein in the appended claims. 85

In the drawings, Figure 1 is a top plan view of one of the preferred forms of my invention as applied 90 to railway use.

Fig. 2 is a side elevation of the structure shown in Fig. 1.

Fig. 3 is a front end elevation of the apparatus shown in Figs. 1 and 2. 95

Fig. 4 is an enlarged detail of the apparatus shown in Figs. 1 to 3, inclusive, illustrating the method of mounting the plow for disconnection and the conveyer co-operating therewith. 100

Fig. 5 is a detail showing a method of automatically operating the plow shown in Fig. 4 to clear obstructions in the road bed.

Fig. 6 is a detail showing the driving mechanism for one of the conveyers of the 105 apparatus shown in Figs. 1 to 3 inclusive.

Fig. 7 illustrates another form of plow and the mounting therefor, which may be used in connection with my apparatus.

Fig. 8 is another form of my invention, 110 wherein the snow removal apparatus is adapted to be towed along the roadway by a

flat car or the like to receive the snow discharged from the apparatus.

Fig. 9 is a side elevation of the apparatus shown in Fig. 8.

5 Fig. 10 is a front elevation of the structure shown in Figs. 8 and 9.

10 Fig. 11 is a top plan view of another embodiment of my invention adapted for the particular requirements of steam railway use, and

15 Fig. 12 is a side elevation of the structure shown in Fig. 11.

20 Referring now to the drawings in detail, in which like characters of reference are employed to designate similar parts throughout the several views, 7 represents the longitudinal or side bars of the supporting frame, which are mounted on the usual car trucks 8 running on the rails 9. At the forward 25 end of the frame, I provide a cab 10 for the engineer or operator of my improved snow removal apparatus. This cab also contains the means for electrically or otherwise controlling the operation and propulsion of the apparatus, any suitable mechanism and source of power being provided for this purpose.

30 Mounted upon the frame of the apparatus rearwardly of the cab 10 is a supporting frame 11 preferably constructed, as shown, for the conveyer 12 and the mechanism for operating the same. The conveyer may be driven in any suitable manner, the forward roller having bearings in the elongated 35 slotted arms 16 and 17 of the frame 11, for the purposes which will be hereinafter more clearly explained. Positioned forwardly of the lower end of the conveyer 12 is a plow 18, which may be of any suitable configuration and which is supported on an arm 19 swiveling upon a depending bracket 20 secured to the underside of the contiguous frame member 7. At the top of the plow 18 and projecting rearwardly therefrom, I 40 provide an apron 21 hinged to the plow, the free end of this apron lightly bearing upon the upper surface of the conveyer 12, so that as the apparatus moves forwardly and the plow picks up the snow, it will be 45 impossible for it to fall back on to the road bed in transit between the plow share and the conveyer 12.

50 Inclined downwardly from the rear of the plow 18 is a plate 22 having a guideway formed thereon for the rollers 23 carried by the arms 24 connected to the ends of the shaft 25 of the conveyer roller 15. The reference character 26 designates the link also carried by the shaft 25 of the roller 15, to 55 which is connected the cable 27 traveling over pulleys mounted in the brackets 28 and 29, and connected to the counterweight 30, positioned on the opposite side of the apparatus as clearly shown in Fig. 1, this 60 weight being adapted to be functioned to

raise the forward end of the conveyer 12 to the position shown in dotted lines in Fig. 4. The numeral 31 represents a rod pivotally connected to the rear of the plow 18 and adapted to slide within the bracket 70 32, secured to the underside of the frame of the apparatus 7, the free end of the rod normally lying adjacent to the yieldable arm 33, supported by the bracket 35 upon the underside of the frame of the apparatus. Positioned between the free end of the arm 33 and the bracket 34, fixed beneath the car is a spring 41, the extremity of the arm 33 being formed with a seat therefor to which the wire 36 traveling on the pulley 80 37 is connected at one end, this wire traveling beneath the frame of the apparatus and up through the supporting frame 11 to a latch 30^a or other suitable means for releasing the weight 30, as hereinafter set forth. 85

90 From the construction thus far described, it will be manifest that upon the plow share 18 coming in contact with an obstruction, such as a rock or stone, the force of the impact will cause the plow to swivel on its support 20, whereby the pin 38 will slide rearwardly out of its guide slot 39 carried by the arm 40. This movement of the plow also operates to move the rod 31 rearwardly into engagement with the yieldable arm 33, 95 which is forced upwardly against the tension of the expansion spring 41 and exerts a pull on the wire 36 which functions the latch 30^a to release the weight 30. Coincidentally with the rearward movement of 100 the plow 18, as just described, the rollers 23 carried by the forward end of the conveyer 12 will ride upwardly on the guide plate 22, which will give the forward end of the conveyer 12 a sufficient upward impetus 105 to enable the weight 30 to function and draw the conveyer to its upward limit of movement within the slotted arms 16 and 17 to the position shown in dotted lines in Fig. 4.

110 At the upward or rear end of the conveyer 12, I provide a downwardly inclined apron 42, which communicates with a conveyer 43 mounted transversely of the apparatus and emptying on to a movable platform, consisting of the sections 44 and 45, 115 traveling in opposite directions, guard plates 46, 47 and 48 being provided at the ends of the moving sections of the platform to prevent snow falling therethrough. This platform is preferably formed with a rim 49, 120 having a central opening provided with a discharge chute 50. This chute is hinged to the platform and normally forms a closure for the discharge outlet, as shown in Figs. 1, 2, and 3, the position of the chute 125 when in discharging position being shown in dotted lines in Fig. 1. The sections 44 and 45 of the receiving platform may be in the form of conveyers and may be operated in any suitable manner, such, for instance, 130.

as by motors 51 and 52, as are shown connected or geared to the conveyers 12 and 43.

The plow 18 is designed to remove the snow from the surface of the road bed to a depth of approximately three or four inches, the residue being swept up by means of the rotary broom 53 mounted in the housing 54 communicating with the chute 55, leading to the fan 56, which may be driven by a motor 57. As will be noted from Figs. 1 and 2 of the drawings, a pipe 58 is connected to the outlet of the fan by a hinged joint 59, this permitting the movement of the mouth of the pipe 58 relatively to the receiving platform, so that the snow swept up by the rotating broom 53 and drawn into the fan 56 will be delivered to the platform for discharge from the chute 50. The housing 54 in which the rotary broom 53 is mounted is supported by a link 60 connected to the wheel 61 suitably mounted upon the apparatus, so that when it is desired to pass an obstruction, or to store the apparatus, the housing 54 and the broom 53 may be swung in and behind the supporting frame 7, by the manual rotation of the wheel 61.

In the embodiments of my invention shown in Figs. 8 and 9, I have illustrated a snow removal apparatus, which is towed by a car 62, the snow removal apparatus in this instance being provided with the ordinary traction wheels 63 and 64, so that it may operate upon the road bed beside the rails 9. In this showing the snow is picked up by the plow 18 and passes to the conveyer 12 from where it is discharged to the apron 42 on to the transversely traveling conveyer 43, this latter conveyer discharging the snow on to the car 62. Similarly to the construction shown in Figs. 1, 2, 3, and 4, in the embodiment now being described, I provide a rotary broom 53, operating in a housing 54 communicating with a fan 56 having a discharge pipe 58 to deliver the snow swept up by the broom 53 to the carrying car 62. The fan 56 in this instance may be operated by a motor 65 geared thereto as herein shown, and the broom 53 and the conveyers 12 and 43 by the motors 66, 67 and 68, respectively. To facilitate traction and also to loosen the snow over which the plow 18 passes, I provide a perpendicular broom 69 supported transversely of the forward truck 70, as shown.

As before stated, in connection with the embodiments of my invention shown in Figs. 8 and 9, the snow removal apparatus is towed by the car 62, for which purpose the latter is provided with the arms 71 and 72 projecting diagonally therefrom and terminating in the bracket 73, having an eye 74 formed thereon, to which the hook 75 is connected by the link 76. The reference character 77 indicates an electric cable carried

by the car 62 and wound about a drum 78 carried by the supporting frame 11 of the snow removal apparatus, this cable being employed to convey power to the controlling means 79 of the apparatus. It will be observed that the apparatus is connected to the hook 75 supported from the car 62 by a tow line 80 wound about a drum 81 carried on the platform 82 and manually controlled by any suitable means, such as indicated by 83. By this means, the relative positions of the receiving car 62 and the snow removal apparatus may be varied longitudinally, so that the full load of the snow discharged from the pipe 58 and conveyer 43, will be evenly distributed upon the car 62. The carrier car is designed to travel at a predetermined rate of speed and to tow the snow removal apparatus under certain designated conditions, which will render the operation of both most efficient, and if anything should arise to vary these predetermined conditions, which would impede the movement of the apparatus relatively to the towing car 62, the apparatus would be immediately uncoupled from the towing car by means of the breaking or opening of the link 76, between the bracket 73 and the hook 75, this link under ordinary conditions of use being sufficiently strong to permit of the taking up and unwinding of the tow line 83 through the medium of the controlling means 79.

In lieu of the fixed plow 18, shown in Figs. 8 and 9, I may if desired employ a modified construction, such as illustrated in Fig. 7, the plow share being indicated at 18^a to the lower portion of which is attached the arm 18^b provided with a rack 18^c, the teeth of the rack 18^c being held in mesh with the pinion 18^d by means of the spring 18^e, so that upon the plow coming in contact with an obstruction, it would pivot at 18^f, motion thereby being imparted to the pinion 18^d, which meshing with the segment 18^g will move the plow rearwardly and upwardly so that it will pass over the obstruction.

In the form of my invention illustrated in Figs. 11 and 12, which is particularly adapted to the purpose of steam railways, the plow 18 is mounted similarly to that in the construction shown in Figs. 8 and 9, as are the conveyers 12 and 43, and the apron 42 communicating therewith. The conveying apparatus and plow are preferably supported on a flat car, as shown, on the forward truck of which is mounted a broom extending transversely of the car, this broom being similar to that shown in Fig. 9 and designated by reference character 69. The conveyers 12 and 43 may be operated by an engine 84 connected by a piping 85 to the source of power 86, which, in the present instance, is a locomotive.

In all of the embodiments of my inven-

tion, herein shown, I have found it desirable to journal the operating parts in demountable bearings so that the snow removal apparatus may be readily disassembled and stored during those seasons in which there is no necessity for its employment. It will be obvious that by the use of my invention, snow removal will be greatly facilitated and that where the embodiment shown in Figs. 1, 2, 3, and 4 is employed on a double track street line, the removal apparatus may operate on one track, while the carrier car travels on the adjoining track, the speed of the apparatus and car being so regulated that the snow being discharged from the chute 50 will be distributed longitudinally on the carrying car to insure a full load. Many other advantages of the employment of my invention both from the viewpoint of economy and efficiency, will be manifest, particularly to those interested in snow removal from street railway tracks located beneath elevated structures, where the supporting pillars for the elevated structures are positioned quite close to the tracks on the street surface. Where, for instance, it is necessary to pass a pillar, the plow 18, the conveyer 12 and broom housing 54 may be swung on their supports 9, 11 and 60, respectively, to a position, which will enable the apparatus to pass the pillar without any portion thereof coming in contact therewith. This is only one of the many advantages of the employment of my invention, under certain specific conditions such as stated, the range of use of my invention being practically unlimited without departing from its basic principle.

Having thus described my invention what I claim as new herein and desire to secure by Letters Patent is:

1. In a snow removal apparatus, the combination of conveyers traveling longitudinally and transversely thereof, a plow communicating with the longitudinally operating conveyer, means for propelling said apparatus, said means comprising a vehicle operating parallel to said apparatus and forming a receiver for the load delivered from the apparatus, and an adjustable towing connection between said vehicle and said apparatus, whereby the relative positions of said vehicle and said apparatus may be varied to effect an equal distribution of the load upon the vehicle.

2. In a snow removal apparatus, the combination of conveyers traveling longitudinally and transversely thereof, a plow communicating with the longitudinally operating conveyer, means for propelling said apparatus, said means comprising a vehicle operating parallel to said apparatus and forming a receiver for the load delivered from the apparatus, an adjustable towing connection between said vehicle and said

apparatus, and means embodied in said adjustable towing connection to effect the breaking thereof under certain predetermined conditions, whereby the relative positions of said vehicle and said apparatus may be varied to effect an equal distribution of the load upon the vehicle.

3. In a snow removal apparatus, the combination of conveyers traveling longitudinally and transversely thereof, a plow communicating with the longitudinally operating conveyer, means for automatically operating said plow to raise the same out of functioning position when coming in contact with a solid obstacle in its normal path of movement, and means for propelling said apparatus, said means comprising a vehicle operating parallel thereto and forming a receiver for the load delivered from the apparatus, and an adjustable towing connection between said vehicle and said apparatus, whereby the relative positions of said vehicle and said apparatus may be changed to effect an equal distribution of the load upon the vehicle.

4. In a snow removal apparatus, the combination of conveyers traveling longitudinally and transversely thereof, a plow communicating with the longitudinally operated conveyer, means for maintaining said plow in functioning position against a yielding element, said means being capable of automatically operating to raise said plow out of functioning position upon said plow coming in contact with a solid obstacle in its path of movement, means for propelling said apparatus, said means comprising a vehicle operating parallel to said apparatus and forming a receiver for the load delivered from the apparatus, and means for changing the relative positions of said vehicle and apparatus, whereby the load may be equally distributed upon the vehicle.

5. The combination with a snow removal apparatus of a vehicle operating parallel to said apparatus and forming a receiver for the snow removed by said apparatus, and means for changing the relative positions of the removal apparatus and the receiving vehicle, whereby the snow delivered from said removal apparatus will be equally distributed on the receiving vehicle.

6. The combination with a snow removal apparatus of a vehicle adapted to receive the snow removed by said apparatus, means of connection between said apparatus and said receiving vehicle, whereby said apparatus may be towed by said vehicle in a line parallel thereto, means for discharging the snow removed by said apparatus into the receiving vehicle, and means for changing the relative positions of said receiving vehicle and said apparatus to effect an equal distribution of the load upon the former.

7. In a snow removal apparatus, the com-

bination of a self-propelled vehicle and a
vehicle adapted to be towed thereby, means
carried by the latter vehicle to remove the
snow from the road bed, means for deliver-
5 ing the snow removed to the towing vehicle,
and means for changing the relative posi-

tions of said vehicles whereby the snow de-
livered to said vehicle may be equally dis-
tributed thereon.

In testimony whereof I have hereunto set 10
my hand this 1st day of April, 1915.

DOUGLAS K. WARNER.
